(57) **CLAIM**

The ornamental design for a vapor pen mouthpiece, as shown and described.

DESCRIPTION

FIG. 1 is a bottom perspective view of a front side of a vapor pen mouthpiece in accordance with the claimed design; FIG. 2 is a top perspective view of the right side of the vapor pen mouthpiece of FIG. 1;

FIG. 3 is a front side elevational view of the vapor pen mouthpiece of FIG. 1, with a rear side elevational view being the same;

FIG. 4 is a right-side elevational view of the vapor pen mouthpiece of FIG. 1, with a left side elevational view being the same;

FIG. 5 is a top plan view of the vapor pen mouthpiece of FIG. 1; and,

FIG. 6 is a bottom plan view of the vapor pen mouthpiece of FIG. 1.

The dash-dot-dot broken lines in the drawings represent portions of the vapor pen mouthpiece that form no part of the claim.

1 Claim, 5 Drawing Sheets
